UNITED STATES PATENT OFFICE.

ROBERT HEAD, OF NEW YORK, N. Y., ASSIGNOR TO PINE HILL CRYSTAL SPRING WATER CO., OF NEW YORK, N. Y., A CORPORATION OF NEW YORK.

COMBINED CLOSURE AND FAUCET.

1,017,756.

Specification of Letters Patent.

Patented Feb. 20, 1912.

Application filed August 3, 1910. Serial No. 575,322.

To all whom it may concern:

Be it known that I, ROBERT HEAD, a citizen of the United States, residing in the city of New York, borough of Manhattan, 5 county and State of New York, have invented a certain new and useful Combined Closure and Faucet, of which the following is a specification.

This invention is a faucet adapted especially for use in drawing potable liquids, such as water, directly from a container, although it will be apparent that it is capable of general application.

The faucets heretofore used, or suggested, 15 for drawing liquids direct from the container are not only complicated in structure, but necessarily involve the introduction of air inlet tubes, or other devices, within the container. It will be manifest that these 20 are disadvantages, both from a mechanical and hygienic standpoint, and the present invention overcomes them in a simple and effective manner.

The invention comprises an improvement 25 in faucets wherein the liquid outlet and the air inlet to the container are located at the mouth of the container.

A further feature of the invention is a device coöperating with the faucet whereby 30 the latter may be secured in place on the mouth of the container.

A further feature of the invention consists of a stopper and a faucet as a unitary structure adapted to be applied to the mouth 35 portion of a container for the purpose of closing the mouth and providing means for drawing liquid therefrom.

In the accompanying drawings I have 40 illustrated a practical embodiment of the invention, but the construction shown therein is to be understood as illustrative, only, and not as defining the limits of the invention.

Figure 1 is a perspective view illustrating 45 my combined faucet and closure applied to the container of a water cooler for the purpose of dispensing liquid directly from the container, said liquid being cooled in the container. Fig. 2 is a vertical longitudinal 50 section through the faucet. Fig. 3 is a rear elevation of the combined faucet and closure illustrating one embodiment of means for attaching the faucet to a container exteriorly to the latter. Fig. 4 is a plan view 55 of the combined faucet and closure in the

position which it occupies when applied to a container, the mouth of the latter being indicated in dotted lines.

The combined faucet and closure shown in Figs. 2, 3, and 4 embodies a body portion, 60 A, which is provided with a liquid discharge passage, B, and an air passage, C, both of said passages being produced in the material composing the body.

The body is made, preferably, of metal 65 cast in a single piece, although other materials may be employed, and at one end said body is exteriorly threaded at a for the reception of a female threaded portion of a member, D, whereby the member, D, may be 70 screwed upon, or unscrewed from, body, A. The liquid discharge passage extends through the body. The air passage, C, is produced in body, A, at one side of liquid passage, B, the cross sectional area of the 75 air passage being considerably smaller than the corresponding area of the liquid passage. One end of the air passage, C, terminates in a right angular extension, c.

Body, A, of the faucet is provided at its 80 inner end with a flange, a', and at its outer end said body is adapted to receive a plate, E, to be hereinafter described. A stopper, F, is fitted upon the body exteriorly thereto, and is positioned between plate, E, and 85 flange, a', whereby the stopper is retained in position upon the body. The stopper, F, may be composed of rubber, or any other material adapted to secure good frictional contact with the wall forming the mouth 90 portion of a container.

Member, D, which is screwed upon the threaded part, a, is provided with a flange, d, adapted to engage with plate, E, for the purpose of confining the plate in operative 95 position between said flange of member, D, and stopper, F. The flange of member, D, incloses the angular end portion, c, of air inlet passage, C, and said flange produces a chamber, d', between itself and plate, E. 100 An aperture, d², is formed in the flange, d, for the purpose of admitting air to chamber, d', the air being free to flow through said chamber and to enter the angular end, c, of passage, C. The flange, d, thus incases 105 the air inlet to passage, C, for the purpose of precluding the admission of dust, etc. into the air passage, and by providing holes, d², in the underside of flange, d, the admission of dust to chamber, d', is minimized. 110

Member, D, is provided with a depending tube, e, and with a tubular neck portion, e', said tube, e, constituting a liquid outlet from the faucet, which liquid outlet is adapted for communication with liquid discharge passage, B, when a liquid controlling valve, G, is opened. Member, D, is provided, furthermore, with a shoulder, g, between tube, e, and liquid passage, B, said shoulder, g, 10 constituting the seat for liquid controlling valve, G. From this valve projects a stem, g', which passes through tubular neck, e', and to the outer end of said stem is secured a push piece, G', positioned exteriorly with 15 reference to the tubular neck, e'. A spring, G², loosely encircles valve stem, g', and acts against the push piece for holding the valve normally on seat, g, thus cutting off the flow of liquid through the faucet. The inner end 20 of spring, G², is seated against a cross piece, g², positioned within neck, e', through which cross piece passes the valve stem, g', said cross piece thus serving as a guide for the valve stem, and as a seat for the valve 25 spring.

For the purpose of precluding the admission of liquid into air passage, C, I employ a valve adapted to control said air passage. Various forms of valves for the air passage 30 may be employed, and in Figs. 2 and 3 the valve is shown as consisting of a piece of flexible material, H, positioned at the inner end portion of body, A, and extending across that end of passage, C. Valve, H, may be 35 composed of leather, rubber, rubber fabric, or any other suitable flexible material, and in Fig. 3 the valve is represented as a curved piece of material secured in position by a suitable fastening device, such as h. The 40 valve is fastened at one end securely to the faucet, while the other end of said valve is positioned over the end of air passage, C. For the purpose of keeping the valve in a 45 closed position I employ a spring, I, the same being shown in Fig. 3 as a leaf spring secured at one end firmly to the faucet by a screw, i, the other end of said leaf spring being free and overlapping that part of valve, H, which covers the extremity of air 50 passage, C, whereby the spring operates to close the air valve. The function of the air valve is, mainly, to preclude the leakage or escape of liquid from the container through 55 the air passage, but when liquid is withdrawn from the container by opening the liquid controlling valve, G, air valve, H, should be free to open for the purpose of admitting air to the container at the same time that liquid flows out of the container. 60 In the construction shown, there is employed means operable by the liquid controlling valve for removing tension exerted by spring, I, upon the air valve, H, said means consisting, preferably, of a rod or stem, I', 65 extending loosely through the faucet. One

end of stem, I', is attached to, or contacts with, spring, I, as shown by dotted lines in Fig. 3, the other end of said stem, I', being spaced with reference to valve, G, and positioned in the path of said valve, whereby the 70 opening of valve, G, causes valve, G, to engage with stem, I', and press said stem and the spring inwardly.

Plate, E, is provided with short arms, j, extending from diametrically opposite sides 75 of the faucet, as shown in Fig. 3, and these arms are provided with angular ends, j'. Through the end portions of the arms pass the short shafts, J, which carry cams, J', said shafts having the thumb nuts, j², for 80 the purpose of clamping the cams firmly in their adjusted positions.

The operation of the invention as thus far described is as follows: For applying the combined faucet and closure to a container, 85 such as a bottle, K, of a water cooler L shown in Fig. 1, the body portion, A, and plug, F, are inserted into the mouth portion, k, of the container shown in dotted lines in Fig. 4. The arms, j, of plate, E, are positioned exteriorly to the container, and cams, J', are turned for engagement with the shoulder, k', on the mouth of the container, after which thumb nuts, j², are tightened 90 for the purpose of securing the cams firmly 95 in position. The stopper and faucet are held against displacement on the container and they close the mouth of said container. The container, K, with the stopper and faucet applied thereto may now be placed 100 in the inclined position shown in Fig. 1, said container resting upon a cooler L, supported on a stand, z. When it is desired to draw a quantity of water from the container it is only necessary to press the 105 push piece, G', inwardly, thus unseating valve, G, and permitting liquid to flow from the container through passage, B, and liquid outlet tube, e. The continued inward movement of valve, G, acts against 110 stem, I', and presses it inwardly so as to remove spring, I, from valve, H. When a certain quantity of liquid shall have been withdrawn from the container, the level of 115 the liquid in the container is lowered and the area of an air space or chamber in the container is increased so that air will pass through the passage, C, and open valve, H, sufficiently for the air to bubble through the liquid present in the container. As liquid 120 continues to be drawn from the container by keeping the valve, G, in an open position, the air will continue to flow through passage, C, and bubble through the liquid contents of the container, but when the pressure is removed from push piece, G', spring G², returns valve, G, to a closed position, and spring, I, acts to press valve, H, to a closed position across the inner end of passage, C, whereby valves, G and H, are closed 125 130

so that no further liquid can flow through passage, B, from the container, nor can air be admitted to the container through the passage, C. The stopper and faucet may be used repeatedly in connection with other containers adapted for use on the cooler.

Having thus fully described the invention, what I claim as new, and desire to secure by Letters Patent is:

10. 1. A faucet provided with a liquid passage, a valve for controlling the flow of liquid through said passage, an air passage in said faucet for admitting air to a container to replace the liquid which flows from the container through the faucet, the delivery end of said air passage being adapted to be positioned within the container and below the level of the liquid in said container, and a single valve for controlling the flow of air through said passage, said valve being spring pressed and positioned at the delivery end of the air passage.

2. A faucet provided with a liquid passage, a valve for controlling the flow of liquid through said passage, an air passage for admitting air to a container to replace the liquid which flows from the container through the faucet, the delivery end of said air passage being adapted to be positioned within the container and below the level of the liquid in said container, a valve at the delivery end of said air passage, a spring for placing tension on said valve, and means for positively operating said spring so as to relieve the valve from tension.

3. A faucet provided with a liquid passage, an air passage in said faucet, the delivery end of said air passage being adapted to be positioned below the liquid in a container, a single valve in said passage and positioned at the delivery end of the passage for precluding the admission of liquid thereto, and means for placing tension on said valve.

4. A faucet provided with a liquid passage, an air passage the delivery end of which is adapted to be positioned below the liquid in a container, a valve at the delivery end of the air passage for precluding the admission of liquid to said air passage, means for placing tension on the valve, and a device for positively removing tension from the valve.

5. A faucet provided with a liquid passage, a valve for controlling the flow of liquid through said passage, an air passage in said faucet for admitting air to a container to replace the liquid which flows from the container through the faucet, the delivery end of said air passage being positioned within the container and below the level of the liquid in said container, an automatic valve positioned at the delivery end of said air passage for precluding the admission of liquid thereto, means for placing

tension on said automatic valve, and means for removing tension from said automatic valve subsequent to the operation of opening the liquid outlet valve.

6. A faucet provided with a liquid passage, a valve for controlling the flow of liquid through said passage, an air passage in said faucet for admitting air to a container to replace the liquid which flows from the container through the faucet, the delivery end of said air passage being positioned within the container and below the level of the liquid in said container, an automatic valve positioned at the delivery end of said air passage for precluding the admission of liquid thereto, means for placing tension on said automatic valve, and means for removing the tension from the automatic valve, said tension removing means being operated by the movement of the liquid outlet valve and subsequent to the opening of said liquid outlet valve to establish the flow of air into the container at substantially the same time the liquid is permitted to flow out of the container.

7. In a liquid dispensing apparatus, a faucet provided with a stopper, said stopper being adapted to close the mouth of a container, a yoke positioned exteriorly with respect to the stopper, and separate securing devices carried by the yoke on the respective end portions thereof and positioned for engagement with the container, said stopper, yoke and securing devices being readily detachable from the container so as to adapt them for use on different containers.

8. In a liquid dispensing apparatus, a faucet provided with a stopper, said stopper being adapted to close the mouth of a container, a yoke positioned exteriorly with respect to the stopper, and separate cams pivoted on the respective end portions of said yoke, said cams being positioned for engagement with a shoulder of the container, whereby the faucet and the stopper are detachably connected to the container.

9. In a liquid dispensing apparatus, a faucet provided with a liquid passage, a valve for controlling the flow of liquid from a container through said passage, an air passage in the faucet for admitting air to the container to replace the liquid which flows through said liquid passage, the delivery end of said air passage being positioned below the level of the liquid in said container, a single valve for controlling the flow of air through said passage, said valve being positioned at the delivery end of said air passage, means for placing tension on said valve, and means, operated by the liquid controlling valve, for removing tension from said valve.

10. In a liquid dispensing apparatus, a faucet provided with a liquid passage, a valve for controlling the flow of liquid from

- a container through said passage, an air passage in the faucet for admitting air to a container to replace the liquid which flows through said liquid passage, the delivery 5 end of said air passage being positioned below the level of the liquid in said container, an automatic valve positioned at the delivery end of said air passage, said automatic valve opening inwardly to the container and 10 operating to preclude the admission of liquid to said air passage, means for placing tension on the automatic valve, and means, operated by the liquid controlling valve, for removing tension from the automatic 15 valve, whereby air is free to flow through the air passage and to enter the container when liquid is drawn from said container.
11. In a liquid dispensing apparatus, a faucet provided with a liquid passage, a 20 valve for controlling the flow of liquid from a container through said passage, an air passage in the faucet for admitting air to the container to replace the liquid which flows through said liquid passage, the delivery 25 end of said air passage being positioned below the level of the liquid in said container, an automatic valve positioned at the delivery end of said air passage, means for placing tension on said automatic valve, and 30 a slideable stem operated by the liquid controlling valve and coöperating with said tension means for removing tension from

the automatic valve, whereby air is permitted to flow through said air passage and to enter the container when liquid is drawn 35 from said container.

12. In a liquid dispensing apparatus, a faucet provided with a liquid passage, a valve for controlling the flow of liquid from a container through said passage, an air 40 passage in the faucet for admitting air to the container to replace the liquid which flows through said liquid passage, the delivery end of said air passage being positioned below the level of the liquid in said container, an automatic valve positioned at the delivery end of said air passage, a spring 45 acting on the valve to retain the latter normally in a closed position, thus precluding the flow of liquid from the container into 50 the air passage, and a slideable rod operated by the movement of said liquid controlling valve, said slideable rod coöperating directly with said spring for removing tension from the automatic valve when the liquid controlling valve is moved to open the liquid passage.

In testimony whereof I have signed my name to this specification in the presence of two subscribing witnesses.

ROBERT HEAD.
